ASSIGNORS TO MODEL FORM COMPANY, OF CHICAGO, ILLINOIS, A CORPORATION
OF ILLINOIS.

ADJUSTABLE CONNECTING DEVICE FOR DRESS-FORMS.

1,221,549.

Specification of Letters Patent.

Patented Apr. 3, 1917.

Application filed November 26, 1913. Serial No. 803,121.

To all whom it may concern:

Be it known that we, MICHAEL LUERY, THOMAS S. LEVIS, and BEN S. NELSON, citizens of the United States of America, residing in Chicago, county of Cook, and State of Illinois, have invented certain new and useful Improvements in Adjustable Connecting Devices for Dress-Forms, of which the following is a specification.

10 Our invention relates to frictional or yielding clamping and connecting devices, particularly useful for adjustably connecting the sections of dress forms, an object of our invention being to provide an improved 15 device of the above character which is simple, positive in its function as a yielding clamp, and also capable of being locked against adjustment.

In providing devices of the above character for use on sectional adjustable dress forms, it is desirable to have a device which will allow ready adjustment of the form without having to reach inside to vary the clamp, and at the same time hold the form 25 securely in adjustment. It is also desirable to have a device which can be locked to prevent adjustment of the form, and to these ends we have provided an improved mechanism comprising preferably a corrugated or 30 roughened connecting strip adapted to be held by pronged members yieldingly clamped to opposite sides of the strip so as to permit its adjustment, but which members may be firmly held against the strip to prevent adjustment thereof.

For a better understanding of our invention reference is to be had to the accompanying drawings in which like parts in the different views are indicated by like reference 40 characters and in which:

Figure 1 is an interior view of the front half of a dress form embodying our invention;

Fig. 2 is a view of our improved device 45 when in its yielding position;

Fig. 3 is an end view of Fig. 2;

Fig. 4 is a sectional view along line 4, 4 of Fig. 2;

Fig. 5 is an edge view of Fig. 2;

Fig. 6 is a longitudinal sectional view 50 along line 6, 6 of Fig. 2 but with the clamping nut adjusted so as to lock the device and prevent movement thereof;

Fig. 7 is a modified form of the body or 55 fixed member; and

Fig. 8 is another modified form of the same member.

Referring now more particularly to the preferred construction of our invention, it comprises a connecting strip 1 preferably 60 corrugated along its adjustable portion 1¹, and having a slot 1² through which the clamping screw 2 extends. When using the device as a single clamp it is preferably fastened by means of holes 1³ but my invention 65 is capable of use in various forms such as shown at A, B, C, and D of Fig. 1, the form A being that illustrated in detail in Figs. 2 to 6. Prong-shaped members 3, 4, are provided at opposite sides of strip 1, the prong 70 or projecting portions facing each other so as to ride upon the two faces of the strip when it is moved. Member 4 also has guides 4¹ which are adapted to prevent side or pivotal movement of the strip relative to its holding means. The fixed or body member 75 may be secured to the form 5 in various ways such as by means of the screw 2 which extends through member 4 and carries a nut 6 for clamping the piece 4 to the body, rivets 80 10 also being used to prevent rotation of member 4 where desired. Screw 2 also extends through the strip 1 and clamping piece 3, there being a yielding element preferably 85 in the form of a spring 7 positioned between membr 3 and a thumb nut 8.

If it is desired to have the device in its yielding adjustment so that the form may 90 be varied in shape, the thumb nut 8 is placed as shown in Figs. 2 to 4 whereby the strip may be adjusted with relation to the holding elements. By varying the adjustment of nut 8, the clamping elements 3, 4 may be made to yieldingly hold the corrugated strip 1 accordingly.

If it is desired to lock the strip against

longitudinal adjustment, the nut 8 is adjusted as shown in Fig. 6 in which position the projections of members 3, 4 rigidly grip the corrugated surfaces of the strip so as to prevent ready movement thereof.

In Fig. 1, we have illustrated the interior of the front half of a dress form, showing one method of applying our invention to adjustable strips for connecting the different 10 sections. The devices A are as shown in Figs. 2 to 6, and the device B is a double connecting strip having yielding clamps at its two ends. The clamps C are T-shaped having a holding device at each of its three 15 ends and D is a double ended strip secured at its center.

In connection with shoulder portions E, F of forms, it is often desirable that they have both horizontal and vertical adjustment and 20 to this end we provide a T-shaped connecting strip C provided at its three end portions with a clamp similar to that of Figs. 2 to 6. It will be apparent that with this arrangement of a T connecting strip, the shoulder 25 portions E, F, may be adjusted in either horizontal or vertical directions.

In Fig. 7, we have shown another form of the fixed member 4 in which the guiding 30 portions 4¹ are bent back and out so as to provide fastening ears 4² so that the screw 2 need not pass through the form as in Fig. 6. In Fig. 8 the guides 4¹ have ears 4² struck out therefrom.

Although in illustrating our invention we 35 have confined it to several forms, it will be apparent that other modifications will readily suggest themselves and therefore we do not desire to be limited to the exact structures as shown and described but aim to 40 cover all that which comes within the spirit and scope of the appended claims.

Having described our invention what we 45 claim as new and desire to secure by United States Letters Patent is:

1. An adjustable connecting device for 50 dress forms comprising a corrugated sheet metal connecting strip, a body member supporting a pair of engaging elements adapted to ride upon the surface of said corrugations on one side of the strip, a second pair of 55 engaging elements adapted to ride upon the surface of the corrugations on the other side of said strip, means for fastening said strip and body members to the form parts to be connected, and means for yieldingly holding said engaging elements to permit longitudinal adjustment of said strip.

2. An adjustable connecting device for 60 dress forms comprising a sheet metal corrugated connecting strip, a body member supporting a pair of engaging elements adapted to ride upon the surface of said corrugations on one side of said strip, a second pair of

engaging elements adapted to ride upon the surface of the corrugations on the other side 65 of said strip, means for fastening said strip and body members to the form parts to be connected, and means for yieldingly holding said engaging elements to permit longitudinal adjustment of said strip, the last said 70 means being adjustable whereby said engaging elements may be locked to prevent adjustment of the strip.

3. An adjustable connecting device for 75 dress forms comprising a sheet metal corrugated connecting strip, a fixed device comprising engaging elements adapted to ride upon the opposite surfaces of said corrugations, a lock-nut, and resilient means between said nut and certain of said engaging 80 elements whereby said nut may be adjusted so as to permit adjusting movement of the strip under opposing action of said elements or to lock said elements to prevent adjusting movement of said strip.

4. An adjustable connecting device for 85 dress forms comprising an elongated connecting strip adapted to be attached to a section of the form at one end and having a slot extending lengthwise thereof, prong-shaped 90 clamping elements engaging opposite surfaces of the connecting strip, a clamping screw adapted to be fastened to another section of the form and extending through said clamping elements and the strip slot, a lock-nut threaded upon said clamping screw, and resilient means positioned between the nut and the pronged clamping elements whereby 95 said nut may be adjusted for varying the clamping tension acting upon said clamping elements.

5. In combination with two adjacent garment form sections, a connecting plate secured at one end to one of said sections, offset therefrom near said secured end and extending in a straight line from said offset over the proximate part of the other section, out of contact with said sections except at its secured end and with all other parts except 100 at its clamping point hereinafter mentioned, a spacing member interposed between said connecting plate and the latter section, a spring pressed friction clamp bearing against said plate opposite to said spacing member and a stud attached to the latter section, 110 passing through said plate, spacing member and clamp.

6. In combination with two adjacent garment form sections, a connecting plate secured at one end to one of said sections, offset therefrom at said secured end and extending in a straight line from said offset over the proximate part of the other section, out of contact with said sections except at 115 its secured end and with all other parts except at its clamping point hereinafter men-

tioned, a spacing member interposed between said connecting plate and the latter section, a yieldingly held friction clamp bearing against said plate opposite to said spacing member and a stud attached to the latter section, passing through said plate, spacing member and clamp.

Signed by us at Chicago, county of Cook

and State of Illinois, in the presence of two witnesses.
